UNITED STATES PATENT OFFICE.

RUDOLPH F. STEHLIK, OF CHICAGO, ILLINOIS, ASSIGNOR TO AUTOMATIC ELECTRIC INC., OF CHICAGO, ILLINOIS, A CORPORATION OF DELAWARE.

TELEPHONE SYSTEM.

Application filed November 3, 1926. Serial No. 145,949.

The invention relates to telephone systems in general, but is more particularly concerned with telephone systems in which non-numerical preselectors or line switches are used to automatically connect lines of one group to idle trunk lines of another group. The principal object of this invention is the production of new and improved control circuits for a group of lineswitches for use in a system of this kind.

A feature of this invention is that all the individual line relays of the lineswitches of a group have been dispensed with, and a group of common line relays, considerably less in number than the number of lineswitches in the group, is substituted therefor. Thus, a material saving is effected in the total number of line relays necessary for a given number of lineswitches.

Lineswitches of the more common types, in which individual line relays are provided for each lineswitch, have the inherent objectionable characteristic that under certain conditions two lineswitches of the same group may operate to connect the two lines terminating in these lineswitches to the same trunk line. This condition occurs whenever the plungers or wipers of two lineswitches (plungers in the case of plunger type lineswitches and wipers in the case of rotary type lineswitches) are standing opposite the same idle trunk line, and are operated simultaneously or very nearly so. According to another feature of this invention, the possibility under any condition of two lines being connected to the same idle trunk line is entirely eliminated.

The object and the features of the invention will be described in detail in the following specification with the aid of the annexed drawings comprising Figs. 1 and 2, which illustrate by means of the usual circuit diagrams one embodiment of the invention as applied to a group of 25 primary lineswitches of the plunger type used in an automatic exchange, although the invention is in no way limited to any particular kind of lineswitch or to there being any particular number of lineswitches in a group.

Referring to the drawings, at the top of Fig. 1, a subscriber's line comprising conductors 62 and 64, terminating at the central exchange in the lineswitch LS^{52} is shown, and at the bottom of Fig. 1, a subscriber's line comprising conductors 62' and 64', terminating at the central exchange in the lineswitch

LS^{54} , is shown. The lineswitches LS^{52} and LS^{54} together with the other lineswitches of the group have common access in their banks to a group of trunk lines, one of which is shown comprising conductors 72, 73, and 74. Each trunk line terminates in an automatic switch (not shown) such as a first selector switch of the Strowger type.

Mechanically, the lineswitches are of the well known plunger type having plungers which control the connection of the subscriber's line with an idle trunk line, the usual individual line relays having been dispensed with. In this type of lineswitch the operating magnet has two armatures and two windings. One armature supports the plunger and, when operated, plunges the plunger into the lineswitch bank; the other armature when operated disconnects the line relay connections from the line conductors (said connections described in detail in later paragraphs). The winding referred to hereinafter as the holding winding or bridge-cut-off winding, when energized, produces sufficient magnetic pull to operate the latter armature only, or hold both armatures operated if they are already operated when this winding is energized. The winding referred to hereinafter as the pull-down winding, when energized, produces sufficient magnetic pull to operate both armatures. The plungers of the lineswitches are further controlled by a common master switch in such a manner that the plungers of all the idle lineswitches of the group are always standing opposite an idle trunk.

A group of common line relays substituted for the individual line relays, controls the battery and ground connections to the pull-down windings of the operating magnets of all the lineswitches of the group. This group of common line relays with other auxiliary relays is shown in the middle of Fig. 1 in two rows.

To most clearly describe the connections of the group of common line relays with the conductors of this group of 25 lines, the 25 lines are assumed to be divided into five subgroups. Each line is designated by a numeral of two digits, the tens digit designating the subgroup containing the line, and the units digit designating the particular line in that subgroup. In Fig. 1, the upper row of line relays, namely relays 210, 220, 230, 240, and 250, are the subgroups of "tens" 110

designating line relays one being provided for each subgroup and designated to correspond therewith; the lower row of line relays, namely, relays 301-305, inclusive, are 5 "units" designating line relays. One conductor of each of the lines of each subgroup is connected to the tens line relay whose tens 10 designating digit is the same as that of the subgroup. The other conductor of each line is connected to the units line relay having the same units designation as the line. For example, one conductor of each of the lines numbered 51-55, inclusive, is connected to 15 tens line relay 250 by way of common tens marking conductor a^5 . Conductor 62 of the line terminating in lineswitch LS^{52} , this line being line No. 52, is one of these. Furthermore, one conductor of each of the lines numbered 12, 22, 32, 42, and 52 is connected to 20 units line relay 302 by way of common units marking conductor b^2 , conductor 64 of line No. 52 terminating in lineswitch LS^{52} being one of these. Thus, one conductor of each line is connected to a certain tens line relay 25 25 and the other conductor is connected to a certain units line relay, but the two conductors of no two lines are connected to the same two line relays.

Fig. 2 is a diagram showing all the operating magnets of the group of twenty-five lineswitches, including magnet 52 of lineswitch LS^{52} and magnet 34 of lineswitch LS^{34} . The numerical designation of each magnet corresponds with the number of the line terminating in the lineswitch with which the magnet is associated. The magnets have been shown arranged so as to most conveniently show the circuit connections of their pull-down windings as controlled by the separate line relays. The magnets associated with the lines of each subgroup appear in one horizontal row with the subgroup or tens marking line relay, to which one conductor of each of the lines of that subgroup is connected, directly to the left. The magnets of each row are arranged in numerical order so that magnets with the same units designation appear in the same vertical row. Each units line relay, to which one conductor of each of the lines having the same units designation is connected, appears directly underneath the vertical row of magnets associated with these lines.

The connections between the common line 55 relays and the operating magnets of the lineswitches are such that when a call is initiated over a certain line, the particular units line relay to which one conductor of the calling line is connected is operated to connect battery potential to one terminal of the pull-down winding of all the operating magnets in the associated vertical row, which includes the operating magnet of the calling line, and the particular tens line relay to which the 60 other conductor of the calling line is con-

nected is operated to prepare the connection of ground potential to the other terminal of the pull-down winding of all the operating magnets in the associated horizontal row which also includes the operating magnet 70 of the calling line. Thus, the circuit for the pull-down winding of the operating magnet of the calling line is established, which magnet operates and effects the operation of the lineswitch to connect the calling 75 line to an idle trunk.

To further describe the invention, a detailed description of the operation of a lineswitch in extending a connection from a subscriber's line to an idle trunk line will be 80 given. For this purpose, referring to Fig. 1, it will be assumed that the subscriber on the line comprising conductors 62 and 64 removes his receiver to initiate a call. Responsive thereto, a bridge is closed across the line 85 conductors which closes a circuit which may be traced from ground by way of resting contact and armature 111, armature 95 and the resting contact, common tens marking conductor a^5 , individual tens marking conductor 125, armature 65 and the resting contact, line conductor 62, over the bridge at the calling substation, line conductor 64, resting contact and armature 66, individual units marking conductor 122, common units marking conductor b^2 , resting contact and armature 102, the common units line relay 302 to battery. Relay 302 operates and performs the following circuit changes: At armatures 312, 322, 332, 334, and 352, battery potential is connected through resistance 113 to the lower terminals of the pull-down winding of magnets 12, 22, 32, 42 and 52 of the corresponding lineswitches, respectively. (See Fig. 2.) At armature 362 the initial energizing circuit for 105 relay 302 is opened by separating the normally closed contacts controlled by this armature, and a locking circuit is closed for this relay in series with relay 90 and 100, which circuit may be traced from ground by way of the 110 resting contact and armature 111, through the winding of relay 90, through the winding of relay 100, armature 361 and the resting contact, armature 362 and the working contact through the winding of relay 302 to battery. 115 At armature 372 a circuit is prepared which will be described presently.

Both relay 90 and 100 energize in the circuit traced above. Relay 100, in operating, disconnects the upper terminals of relays 120 301-305 from the common conductors b^1 - b^5 at armatures 101-105 respectively, and at armature 106 closes the circuit for relay 110. Relay 110, by reason of its slow-acting characteristic, does not operate its armature 111 125 until an appreciable time after its circuit is closed. Relay 90, in operating, removes the normal short circuit around relay 210, 220, 230, 240, and 250, at armatures 91, 92, 93, 94, and 95 respectively. Tens line relay 250 now 130

operates over the circuit from ground by way of the resting contact and armature 111, through the winding of relay 250, armature 85 and the resting contact, conductor a^5 , conductor 125, armature 65 and the resting contact, line conductor 62, over the bridge at the calling substation, line conductor 64, resting contact and armature 66, conductor b^2 , armature 372 and the working contact through resistance 112 to battery. Relay 250, in operating its armatures 251-252, prepares a circuit for connecting ground potential to the upper terminals of the pull-down winding of operating magnets 51-55 of the corresponding lineswitches, respectively, (see Fig. 2). At armature 256 relay 250 closes a locking circuit for itself which may be traced from ground by way of the resting contact and armature 111, through the winding of relay 250, working contact and armature 256, resting contact and armature 246, resting contact and armature 236, resting contact and armature 226, resting contact and armature 216, through the winding of relay 80 to battery. Relay 80 also operates over this circuit and at armatures 81-85 disconnects common conductors a^1-a^5 from the upper terminals of relays 210, 220, 230, 240, and 250, respectively, and at armature 86 completes the circuit for placing ground potential on the upper terminal of the pull-down winding of magnets 51-55, inclusive. With both relays 80 and 100 operated, the line relays are disconnected from all the lines of the group. Therefore no other line can initiate a call at this particular time.

Since ground potential has now been connected to upper terminal of the pull-down winding of magnet 52, and battery potential through resistance 113 has been connected to the lower terminal of this winding, magnet 52 energizes and operates the plunger (not shown) which causes springs 67, 68, 69, and 70 to close, thereby extending the connection by way of trunk conductors, 72, 73, and 74 to the first selector switch terminating this trunk. In operating, magnet 52 also disconnects the line conductors 64 and 62 from the tens marking conductor a^5 and the units marking conductor b^2 at armatures 65 and 66, respectively. By the closure of springs 69, ground potential is applied to conductor 75 connected to the bank contact in the master switch bank associated with the trunk comprising conductors 71, 72, 73, and 74, which causes the master switch to operate and position the plungers of all the idle lineswitches of this group opposite the next idle trunk. This operation is well known to those skilled in the art and consequently need not be further described.

As a result of the extension of the connection to the selector switch terminating the trunk comprising conductors 72, 73, and 74, this selector switch operates in the well

known manner and connects ground potential to the release conductor 73, thereby closing a holding circuit for the holding winding of magnet 52 to hold this relay operated and hold the plunger in operated position, and also apply ground potential to the private normal conductor 63 to mark the subscriber's line busy.

The slow-acting characteristic of relay 110 is so timed that it does not operate its armature 111 until after all the foregoing operations described after its circuit was closed at armature 106, have taken place; that is, until after the selector switch terminating in the trunk comprising conductors 72, 73, and 74 has had time to complete a holding circuit for magnet 52 by the application of ground potential to the release conductor 73, and the master switch has performed its operation. As soon as these operations have taken place, however, relay 110 operates its armature 111 thereby opening the holding circuit for relays 250, 90, 100, and 302. These relays will then deenergize and restore their armatures to normal. Relay 100, in deenergizing, also opens the circuit of relay 110 which also deenergizes a short time thereafter and restores armature 111 to normal. The common line relay equipment is now ready to take care of another call. Further extension of the connection will take place in the well known manner.

When the calling subscriber replaces his receiver at the termination of a conversation, the first selector is released in the well known manner, disconnecting ground potential from the release conductor 73, thereby opening the holding circuit for magnet 52 and also marking the line at substation to the calling substation idle. Magnet 52 thereupon deenergizes, restoring its armatures 65 and 66 to normal and also releasing the plunger to separate springs 67, 68, 69, and 70.

When the subscriber on the line comprising conductors 62' and 64' initiates a call, magnet 34 of lineswitch LS^{34} is operated similar to the way magnet 52 of the lineswitch LS^{52} was operated. In this case, units line relay 304 is operated to apply battery potential through resistance 113 to the lower terminals of the pull-down windings of magnets 14, 24, 34, 44, and 54 at armatures 314, 324, 334, and 354, respectively, and tens line relay 230 is operated to prepare a circuit for placing ground potential on the upper terminals of the pull-down windings of magnets 31-35 at armatures 231-235, respectively. Magnet 34, in operating, operates the plunger of the lineswitch LS^{34} which connects the subscriber's line to the trunk line opposite which the plunger is positioned at the time the call is initiated.

As previously stated, a special feature of the invention is that the possibility of two lineswitches connecting their associated lines

to the same trunk line is entirely eliminated. It is clear from the foregoing description that if a second call is initiated after relays 100 and 80 have operated, the operation of the lineswitch of the second calling line is delayed until the first call has been taken care of and the plungers of the remaining lineswitches, including the plunger of the lineswitch of the second calling line, are positioned opposite another idle trunk.

To further describe how the above feature is accomplished, the operations resulting when two subscribers remove their receivers simultaneously will now be described. For example, it may be assumed that the subscriber on line comprising conductors 62 and 64, and the subscriber on line comprising conductors 62' and 64', remove their receivers to initiate a call simultaneously. Upon the removal of the receiver at these substations, a circuit is simultaneously established for units line relay 302, and for units line relay 304. Both relays 302 and 304 operate. Relay 302, appearing first in the series, opens its initial energizing circuit and closes a holding circuit for itself at the armature 362 in series with relays 100 and 90 as described previously. Relay 304 also operates its corresponding armature 364, opening the initial energizing circuit by separating the springs controlled thereby. However, no holding circuit is closed for relay 304 since armature 362 has separated from its resting contact. Therefore relay 304 deenergizes and remains deenergized until after its initial energizing circuit is again closed upon the deenergization of relay 100. This, as described above, does not take place until the subscriber's line comprising conductors 62 and 64 has been connected with the trunk line opposite which the plungers have been standing, and the master switch is operated to move the remaining plungers opposite the next idle trunk. With relay 304 in a deenergized state, no circuit can be closed for the operating magnet 34 of lineswitch LS^{34} at this time. The circuit of magnet 52 is closed, as previously described, however, causing lineswitch LS^{52} to operate and connect its associated line to an idle trunk. After lineswitch LS^{52} has operated and the master switch has selected another idle trunk, relays 90, 100, 80, and 110 deenergize, after which the circuit of magnet 34 is closed to operate lineswitch LS^{34} to extend the second connection over the other idle trunk line.

Another case may now be considered in which two subscribers, whose lines are connected to the same units line relay, remove their receivers simultaneously. For example, it may be assumed that the subscriber on the line comprising conductors 62 and 64 and the subscriber on the line whose operating magnet is magnet 42, removes their receivers simultaneously to initiate calls. Conductor 64

and one conductor of the latter line are both connected to conductor b^2 . Conductor 62 is connected to conductor a^5 , while the corresponding conductor of the latter line is connected to conductor a^4 . When the two subscribers remove their receivers, two parallel circuits are closed for relay 302, one circuit including conductors 62, 64, 122, and b^2 in series as previously traced, and the other circuit including the two line conductors of the other calling line, a conductor corresponding to conductor 122, and conductor b^2 in series. Relay 302 operates as previously described, connecting battery potential through resistance 113 to one terminal of magnet 12, 22, 32, 42, and 52, connecting battery potential through resistance 112 to conductor b^2 , and closing a locking circuit for itself in series with relays 100 and 90. Relay 90, in operating, opens the short circuit around relays 210, 220, 230, 240, and 250. Both relays 250 and 240 operate, relay 250 operating over a circuit including conductor b^2 , line conductors 62 and 64, and conductor a^5 in series, and relay 240 operating over a circuit including conductor b^2 , the two line conductors of the other calling line, and conductor a^4 in series. Relay 240, in operating, prepares a circuit for connecting ground potential to the other terminal of magnets 41-45 at armatures 241-245, respectively, and closes a holding circuit for itself at armature 246 in series with relay 80. Relay 250, in operating, temporarily performs similar circuit changes but does not close a locking circuit for itself at armature 256, since armature 246 has separated from its resting contact. Relay 80, in operating, opens the initial energizing circuits of both relays 240 and 250 at armatures 84 and 85, respectively. As a result, relay 250 deenergizes and releases its armatures. At armature 86 of relay 80, the circuit is closed for connecting ground potential to the other terminals of magnets 41-45 inclusive. With relay 250 in a deenergized state, no circuit can be closed for the operating magnet 52 of lineswitch LS^{52} at this time. Since the circuit for magnet 42 is completed, however, lineswitch LS^{42} (not shown) operates to extend the connection to an idle trunk, after which the operated relays in the common line relay group restore to normal. Immediately thereafter, the common line relays function to cause the operation of lineswitch LS^{52} as previously described.

From the foregoing examples, it is clear that only one tens line relay and only one units line relay can be held energized at one time, and consequently the circuit of only one operating magnet relay can be closed at one time. As a result, even though calls are initiated simultaneously, the lineswitches of the calling lines will not operate simultaneously but will operate in succession, the order of operation depending on the position of the line relays.

with respect to the chain locking circuits of the line relays to which each calling line is connected.

This completes the description of the operation of the invention. What is thought new and is desired to have protected by Letters Patent will be specifically stated in the appended claims.

What is claimed is:

1. In a telephone system, a group of lines, a preselecting lineswitch terminating each of said lines, a group of trunks, means in each lineswitch for connecting the associated line to one of said trunks, and a group of line relays less in number than the number of lines in said group of lines for controlling the connecting means in all said lineswitches.
2. In a telephone system, a group of lines, a lineswitch terminating each of said lines, a group of trunks, means in each lineswitch for connecting the associated line to one of said trunks, a group of line relays less in number than the number of said lineswitches, means effective when a call is initiated over any one of said lines for operating certain of said line relays to cause the operation of the connecting means in the lineswitch terminating the calling line to connect the calling line with one of said trunks, and means for preventing the operation of any other line relays after certain of said relays have been operated, until after said calling line is connected to a trunk.
3. In a telephone system, a group of lines, a lineswitch terminating each of said lines, a group of trunks, means in each lineswitch for connecting the associated line to one of said trunks, a group of line relays less in number than the number of said lineswitches, means effective when a call is initiated over any one of said lines for operating certain of said line relays to cause the operation of the connecting means in the lineswitch terminating the calling line to connect the calling line with one of said trunks, and means for preventing the operation of the connecting means in more than one lineswitch at the same time when calls are initiated over two lines simultaneously or nearly so.
4. In a telephone system, a group of lines, a lineswitch terminating each of said lines, a group of trunks, means in each lineswitch for connecting the associated line to one of said trunks, a magnet in each lineswitch for controlling the connecting means, a battery, said magnet being normally disconnected from the poles of said battery, and a group of line relays less in number than the number of magnets for controlling the connection of the poles of said battery to said magnets.
5. In a telephone system, a group of lines, a lineswitch terminating each of said lines, a group of trunks, a magnet in each lineswitch for connecting the associated line to one of said trunks, the magnets of all of said line-
- switches being divided into a plurality of subgroups, a primary line relay for each subgroup, a secondary line relay for the corresponding magnets of each subgroup, a particular primary line relay and a particular secondary line relay being normally connected to each line, and means effective when a call is initiated over one of said lines for operating the primary line relay and the secondary line relay normally connected to the calling line to cause the operation of the magnet of the lineswitch terminating the calling line.
6. In a telephone system, a group of lines, a lineswitch terminating each of said lines, a group of trunks, a magnet in each lineswitch for connecting the associated line to one of said trunks, the magnets of all of said lineswitches being divided into a plurality of subgroups, a primary line relay for each subgroup, a secondary line relay for the corresponding magnets of each subgroup, means effective when a call is initiated over one of said lines for operating one of said primary line relays and one of said secondary line relays to cause the operation of the magnet of the lineswitch terminating the calling line, and means for vitiating the effect of the operation of more than one secondary relay at one time even though calls are initiated over two of said lines simultaneously.
7. In a telephone system, a group of lines, a lineswitch terminating each of said lines, a group of trunks, a magnet in each lineswitch for connecting the associated line to one of said trunks, the magnets of all of said lineswitches being divided into a plurality of subgroups, a primary line relay for each subgroup a secondary line relay for the corresponding magnets of each subgroup, means effective when a call is initiated over one of said lines for establishing initial operating circuits for one of said primary line relays and for one of said secondary line relays to cause the operation of the magnet of the lineswitch terminating the calling line, and means for closing holding circuits and for opening the initial operating circuits for the operated primary line relay and the operated secondary line relay.
8. In a telephone system, a group of lines, a lineswitch terminating each of said lines, a group of trunks, a magnet in each lineswitch for connecting the associated line to one of said trunks, the magnets of all of said lineswitches being divided into a plurality of subgroups, a primary line relay for each subgroup, a secondary line relay for the corresponding magnets of each subgroup, means effective when a call is initiated over one of said lines for establishing initial operating circuits for one of said primary line relays and one of said secondary line relays to cause the operation of the magnet of the lineswitch terminating the calling line, means for clos-

ing holding circuits and for opening the initial operating circuits for the operated primary line relay and the operated secondary line relay, and means for opening said holding circuits a predetermined interval after they are closed.

9. In a telephone system, a group of lines, a lineswitch associated with each of said lines, a trunk line, a group of primary line relays, a group of secondary line relays, each of said lines being normally associated with a certain one of said primary line relays and with a certain one of said secondary line relays, no two lines being associated with the same two relays, means effective when a call is initiated over one of said lines for operating the associated primary line relay, a self-locking circuit for the operated primary line relay, means effective when said self-locking circuit is closed for causing the operation of the secondary line relay associated with the calling line and for disassociating the remaining primary line relays from said lines, and means in each lineswitch jointly controlled by the associated primary line relay and secondary line relay for connecting the associated line to said trunk line.

10. In a telephone system, a group of lines, a group of trunks, a preselecting lineswitch terminating each of said lines for connecting the associated line to the preselected one of said trunks upon the initiation of a call, and a group of line relays less in number than the number of lines in said group for controlling the operation of all of said lineswitches.

11. In a telephone system, a group of lines, a group of trunks, a lineswitch terminating each of said lines for connecting the associated line to one of said trunks responsive to the initiation of a call over the associated line, a group of common line relays for said lines, each line being associated with a different two of said relays, and means controlled by the two relays associated with one of two lines over which calls are initiated simultaneously or nearly so for preventing the two lines from being connected to the same trunk.

12. In a telephone system, a group of lines, a group of trunks, a lineswitch terminating each of said lines for connecting the associated line to the trunk opposite which the lineswitch is standing responsive to the initiation of a call over the associated line, the idle ones of said lineswitches always being positioned opposite the same idle trunk, and moved to

the next idle trunk when a lineswitch is operated, and means for preventing two lineswitches from connecting their associated lines to the same trunk when calls are initiated over the said associated lines simultaneously or nearly so.

13. In a telephone system, a group of lines, a group of trunks, a lineswitch terminating each of said lines for connecting the associated line to the trunk opposite which the lineswitch is standing responsive to the initiation of a call over the associated line, the idle ones of said lineswitches always being positioned opposite the same idle trunk, and moved to the next idle trunk when a lineswitch is operated, and means for causing two lineswitches to operate successively to connect their associated lines to different trunks even though calls are initiated over the said associated lines simultaneously or nearly so.

14. In a telephone system, a group of lineswitches, an operating magnet for each lineswitch, a battery, and a group of common line relays for connecting the poles of said battery to the magnets of said lineswitches.

15. In a telephone system, a group of lineswitches, an operating magnet for each lineswitch, a battery, a group of common line relays for connecting one pole of said battery to one terminal of said magnets, and another group of common line relays for connecting the other pole of said battery to the other terminal of said magnets.

16. In a telephone system, a group of lineswitches, each lineswitch having an operating magnet, a group of common line relays for controlling the operation of said magnets, each lineswitch being normally connected to certain of said line relays, and contacts on each magnet for disconnecting the line relays normally connected to the lineswitch with which the magnet is associated.

17. In a telephone system, a group of lines, each line terminating in a lineswitch, a first and a second group of line relays, the total number of relays in the two groups being less than the number of lines in said group, a relay of the first group being normally connected to one side of each line, and a relay of the second group being normally connected to the other side of each line, and means controlled by the two relays connected to the two sides of a line when a call is initiated over the line for operating the lineswitch of the line.

RUDOLPH F. STEHLIK.
